UNITED STATES PATENT OFFICE.

KENNETH RUSHTON, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

DRIVING-AXLE BOX FOR LOCOMOTIVES.

1,146,659.

Specification of Letters Patent. Patented July 13, 1915.

Application filed May 21, 1914. Serial No. 840,028.

To all whom it may concern:

Be it known that I, KENNETH RUSHTON, a citizen of the United States, residing in Philadelphia, Pennsylvania, have invented 5 certain Improvements in Driving-Axle Boxes for Locomotives, of which the following is a specification.

My invention is particularly adapted for use in connection with the axles of the driving wheels of locomotives which require a 10 heavy and substantial box and which must properly support the springs which, in turn, carry the frame of the locomotive.

One object of my invention is to construct 15 a single box for each axle, the box extending from one side frame to the other and having the proper extended bearing for the axle.

A further object of the invention is to construct 20 the box so that the spring supporting the frame can be mounted thereon so as to clear the frame and to support the springs.

In the accompanying drawings:—Figure 1, is a transverse sectional view through the 25 frame of a locomotive on the line *a—a*, Fig. 3, illustrating my improved axle box; Fig. 2, is a sectional plan view on the line *b—b*, Fig. 3, showing the box in section; Fig. 3, is a side view with the axle in section and 30 the driving wheel omitted; and Figs. 4 and 5, are views illustrating modifications of the invention.

Referring to the drawings, 1, 1 are the 35 two side frames of the locomotive, made in the ordinary manner.

2 is the axle on which are secured the driving wheels 3. The frame 1 has pedestals 4.

5 is the axle box which is mounted in the 40 pedestals. This axle box is made in one piece and extends from one side frame to the other, being arranged to slide between the pedestals 4. In the present instance, there are liners 6 between the pedestals and 45 the box. The box is flanged at 7 so as to hold it against longitudinal movement. Mounted within the box are the usual brasses or bearings 8, and the lower portion of the box has the well 9 of any suitable 50 type secured in place by bolts or other fastenings. This construction may be modified, as desired.

11, 11 are two springs mounted on a support 12 carried by the box 5 and these

springs are properly located directly above 55 the frame 1, so as to be coupled to the other elements of the equalizing gear. Usually the spring support is located in line with the frame and straddles the frame, and, in this instance, the spring support can rest on 60 the axle at any point throughout its length and be properly balanced and supported.

While I prefer to construct the spring support in the manner shown in Fig. 1, it 65 may be modified without departing from the essential features of the invention. For instance, in Fig. 4, I have shown an independent support 12^a at each side of the locomotive made in inverted U-shaped form so as to straddle the frame and support the 70 spring 11 directly above it.

In Fig. 5, I have illustrated another modification where the spring 11 is not directly over the frame 1, as in Fig. 1, and, in this instance, I preferably use two independent 75 double U-shaped spring supports 12^b. One of the U-shaped sections extends over the frame 1 and the other is located between the frames. The spring supports at each side are made independent, but they may be connected, as illustrated in Fig. 1, if desired.

The main feature of the invention is making the axle box in one piece extending from one side of the locomotive to the other and having extended bearings therein for the 85 axle, and so arranged that the spring support may be located on the axle box at any point desired.

When it is necessary to remove the axle box from the frame of the locomotive, all 90 that is necessary is to remove the lower retaining bar or plate 15 and either jack up the locomotive frame or lower the axle with the box clear of the frame, in the ordinary manner.

My improved box will fit any of the standard frames and can be substituted for any of the ordinary boxes of the present construction. The weight of the spring is evenly distributed over the entire length of 100 the journals.

It will be understood that the bearing may be reinforced by ribs, as shown in Figs. 1 and 2, in any manner desired, or it may be of sufficient strength to dispense with the 105 ribs.

The spring support 12, as shown in Fig. 1, has two feet 14 which extend between the

frames 1 and rest on the box 5, and has laterally extending brackets 13 which project over the frames 1 and carry the springs 11, but, as stated above, this construction 5 may be modified without departing from the main features of the invention.

I claim:—

1. The combination of the two side frames of a locomotive, each side frame having a 10 pedestal; an axle box extending from one side frame of the locomotive to the other and mounted in both frames and made as a unitary structure; springs above the side frames; and a spring support for said 15 springs resting on the axle box.
2. The combination of the two side frames

of a locomotive, each having a pedestal; an axle box extending from one side of the locomotive to the other and mounted in the box, said box being made as a unitary structure; springs mounted above the frames; and a spring support having brackets securing the springs and having feet extending between the frames and resting on the axle box. 20

In testimony whereof, I have signed my name to this specification, in the presence of two subscribing witnesses.

KENNETH RUSHTON.
